UNITED STATES PATENT OFFICE.

CHARLES F. OSGOOD, OF CLAREMONT, NEW HAMPSHIRE, ASSIGNOR TO SULLIVAN MACHINERY COMPANY, A CORPORATION OF MASSACHUSETTS.

ROCK DRILL.

Application filed June 2, 1927. Serial No. 196,109

This invention relates to rock drills and more particularly to a hole blowing device for fluid actuated rock drills of the hammer type.

5 An object of this invention is to provide an improved hole blowing device for a fluid actuated rock drill. Another object is to provide an improved hole blowing device whereby the opposing pressures acting on the 10 opposite ends of the fluid distribution valve may be equalized prior to the manual shifting of the valve, thereby greatly reducing the exertion required on the part of the operator. Another object is to provide an im- 15 proved hole blowing device for holding the fluid distribution valve immovable to effect a hole blowing operation and including a manually operable plunger valve extending coaxially through the distribution valve and 20 having a by-pass therein whereby communication between the spaces at the ends of the distribution valve may be established, and as a result the opposing pressures at the ends 25 of the distribution valve may be equalized prior to the manual shifting thereof. These and other objects and advantages will, however, subsequently more fully appear.

In the accompanying drawing there is shown for purposes of illustration one form 30 which the invention may assume in practice.

In this drawing,—

Fig. 1 is a central, longitudinally extending, vertical sectional view taken through a rock drill with which the improved hole 35 blowing device is incorporated.

Figs. 2 and 3 are detail sectional views illustrating the automatic fluid distribution valve and the hole blowing device associated therewith, parts being shown in different op- 40 erative positions.

In this illustrative construction there is shown a rock drill of the fluid actuated hammer type comprising a cylinder 1 having a bore 2 in which is reciprocably mounted a hammer piston 3. The hammer piston 3 is provided with a forwardly projecting striking bar 4 extending through a bore 5 formed within a usual front cylinder head 6. The striking bar 4 is adapted to impart a series 45 of blows to the shank of a hollow drill steel 7. The drill steel 7 is loosely mounted in a usual manner within a chuck bushing 8 secured to a chuck sleeve 9 rotatably mounted within a usual chuck housing 10. As illus-

trated, the rear end of the cylinder bore 2 is 55 closed by a washer 11 while interposed between this washer and a rear head member 12 is a usual ratchet ring 13 to be later referred to. The chuck housing 10, the front cylinder head 6, the cylinder 1, rear washer 11, rear 60 head 12, and the ratchet ring 13 are held in assembled relation in any suitable and convenient manner, for instance by usual side rods or bolts (not shown).

The cylinder 1 has preferably formed integral therewith a valve chest 14 having a bore 15, herein arranged parallel with the cylinder bore 2. Disposed within the bore 15 are oppositely positioned valve sleeves 16 and 17 each having an enlarged central bore 18 and a reduced outer bore 19. As shown in Fig. 1, the valve sleeve 16 has suitably fixed thereto a valve buffer plug 20 while secured to the sleeve 17 is a buffer plug 21 held in position by a suitable nut member 22. Reciprocably mounted within the bores 18 and 19 formed in the sleeves 16 and 17 is an automatic fluid distribution valve 23 herein of the well known three-spool, differential type having reduced end spools 24 and an enlarged 80 central spool 25. Reciprocating movement of the valve 23 in opposite directions is limited by the buffer plugs 20 and 21 in a well known manner. The central spool 25 of the valve shown controls a central inlet port 26, 85 while the end spools 24 respectively control usual exhaust ports 27 and 28 formed at the opposite sides of the inlet port 26 and leading directly to atmosphere. Motive fluid for actuating the piston 3 is supplied and ex- 90 hausted from the rear and front ends of the cylinder bore 2 through combined supply and exhaust passages 29 and 30 respectively communicating with the valve chamber on oppo- 95 site sides of the central inlet 26. The action of the valve 23 is controlled by usual crossed throwing passages 31 and 32, the former connecting the front end of the cylinder bore with the bore 19 at the rear end of the valve, while the throwing passage 32 connects the 100 rear end of the cylinder bore with the bore 19 at the front end of the valve. These throwing passages are controlled by the hammer piston 3 and are employed for alternatively admitting pressure fluid from the cylinder bore to the opposite ends of the distribution valve to effect reciprocation there- 105 of, the pressure fluid admitted to the pas-

sage 31 throwing the distribution valve forwardly while the pressure fluid admitted to the passage 32 throws the valve rearwardly, all in a well known manner.

5 The drill steel 7 is adapted to be intermittently rotated during reciprocation of the hammer piston and this is accomplished by a usual ratchet and pawl mechanism including a rotatable pawl carrier 33 carrying usual 10 spring pressed pawls which cooperate with internal ratchet teeth 34 formed within the ratchet ring 13. Herein preferably formed integral with this pawl carrier and projecting forwardly through the washer 11 and within 15 the rear end of the cylinder bore is a rifle bar 35 having spiral grooves 36 on its periphery. The spiral grooves 36 cooperate with spiral keys 37 carried by a rifle nut 38 threadedly connected within the rear end of the 20 hammer piston 3. As shown, the striking bar 4 of the hammer piston has formed on its periphery throughout a portion of its length straight longitudinally extending grooves 39 which cooperate with straight keys 40 carried 25 by a chuck nut 41 threadedly connected to the chuck sleeve 9. During forward movement of the hammer piston 3 the pawls of the pawl carrier slip over the teeth on the ratchet ring 13 and consequently the hammer piston delivers 30 an unimpeded blow to the shank of the drill steel 7. Upon the return stroke of the hammer piston the pawls engage the ratchet teeth 34, thereby preventing rotation of the rifle bar and consequently during this return 35 stroke of the hammer piston the latter is slightly rotated. Rotation of the piston is transmitted through the straight grooves 39 on the striking bar, straight keys 40 on the chuck nut, the sleeve 9 and the chuck bushing 40 and consequently the drill steel is rotated. The construction described above is usual in 45 rock drills of the type disclosed and further description of the same is herein considered unnecessary.

45 The improved hole blowing device comprises a reciprocable plunger valve 42 extending through a central bore 43 in the distribution valve 23 and slidably mounted in bores 44 and 45 formed in the buffer plugs 20 and 21 respectively. The portion of the valve 42 extending through the bore 43 in the distribution valve and the bore 44 in the buffer plug 20 is reduced, thereby forming a shoulder or 50 abutment 46 adapted to engage the distribution valve as will hereinafter be described. The valve 42 is externally grooved at longitudinally spaced points as indicated at 47 and 48, and these grooves are connected by transverse passages 49 and a central longitudinal 55 by extending passage 50, the passages 49 and 50 forming a by-pass. As shown, radial ports 51 and 52 connect the bores 44 and 45 respectively in the buffer plugs with the bores 19 at the ends of the distribution valve 23. Suitably secured to the forward end of the valve 60

42 is a conveniently located push button 53. A coiled spring 54 seated within a bore 55 formed in the buffer plug 21 and acting against a transverse pin 56 carried by the plunger valve 42 normally tends to hold the 70 valve 42 in its released or inoperative position, as shown in Fig. 3.

In the normal operation of the rock drill, pressure fluid flows through inlet passage 26 and when the distribution valve 23 is in the 75 position shown in Fig. 2, fluid flows past the rear surface of the central spool 25 of the distribution valve and through the passage 29 to the rear end of the cylinder bore 2 where it acts on the rear surface of the hammer piston 3 and moves the latter forwardly to strike a blow on the drill steel 7. The exhaust from the front end of the cylinder bore 2 flows out through the passage 30 past the rear surface of the forward spool 24 and through the 80 exhaust passage 28 to atmosphere. The distribution valve is held in its forward position against the front buffer plug 21 by reason of the larger effective area of the central spool 25. When the hammer piston 3 uncovers the 85 throwing passage 32, pressure fluid is admitted from the cylinder bore to the forward end of the distribution valve and consequently the latter is thrown rearwardly against the 90 rear buffer plug 20 as shown in Fig. 1. Pressure fluid now enters the forward end of the 95 cylinder bore through inlet passage 26 past the forward surface of the central spool on the distribution valve and through passage 30 and consequently the hammer piston is 100 moved rearwardly. The exhaust now takes place through passage 29 past the forward surface of the rear spool 24 and through the 105 exhaust passage 27 to atmosphere. As soon as the hammer piston 3 has uncovered the 110 throwing passage 31, the distribution valve 23 is again shifted to its forward position and this cycle continues throughout the normal 115 operation of the drill.

When it is desired to effect a hole cleansing operation, the operator presses against the push button 53 and moves the plunger valve 42 rearwardly from the position shown in Fig. 3 to the position shown in Fig. 2. At this time the grooves 47 and 48 on the 110 plunger valve 42 and the passages 49 and 50 and radial ports 51 and 52 form a by-pass establishing communication between the opposite ends of the distribution valve 23, thereby causing the opposing pressures at the ends 115 of the distribution valve to be equalized. Upon further rearward movement of the plunger valve 42, the shoulder 46 thereon directly engages the forward end surface of the distribution valve 23, thereby permitting the latter to be manually shifted with facility 120 from the position shown in Fig. 2 to the position shown in Fig. 1 against the relatively small opposing pressure acting on the central spool 25. When the distribution valve 23 is 125 130

held in its retracted position as shown in Fig. 1, pressure fluid flows from the inlet 26 past the forward surface of the central spool 25 of the distribution valve and through the passage 30 to the forward end of the cylinder bore. The pressure fluid flowing continuously to this end of the cylinder bore forces the hammer piston rearwardly against the rear cylinder washer 11 and consequently fluid flows from the cylinder bore through the flutes 41 on the striking bar, through the chuck nut, and thence through the bore in the drill steel 7 to the bottom of the hole. As soon as the manual pressure on the push button is released, the valve 42 will automatically return to its inoperative position and the valve 23 will then resume its normal operation and the drill will again function in the normal manner. This and other uses and advantages of this invention will be clearly apparent to those skilled in this art.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a fluid actuated rock drill of the hammer type, the combination of a cylinder and a hammer piston reciprocable therein, a valve chest and a fluid distributing valve therein controlling both the supply and exhaust of pressure fluid for said cylinder, valve throwing passages between opposed spaces in the valve chest and the cylinder bore for supplying pressure fluid for actuating said valve, and manually operable valve means to establish communication between the valve chest spaces at the opposite ends of the valve for equalizing the pressures and means movable with said valve means to shift and hold the distributing valve immovable.

2. In a fluid actuated rock drill of the hammer type, the combination of a cylinder and a hammer piston reciprocable therein, a valve chest and a fluid distributing valve therein controlling both the supply and exhaust of pressure fluid for said cylinder, valve throwing passages between opposed spaces in the valve chest and the cylinder bore for supplying pressure fluid for actuating said valve, and manually operable means including an element arranged coaxially with said distribution valve and having valve means for establishing communication between the valve chest spaces at the opposite ends of the valve, said element also having means for directly engaging said valve to shift and hold the latter immovable.

3. In a fluid actuated rock drill of the hammer type, the combination of a cylinder and

a hammer piston reciprocable therein, a valve chest and a fluid distributing valve therein controlling both the supply and exhaust of pressure fluid for said cylinder, valve throwing passages between opposed spaces in the valve chest and the cylinder bore for supplying pressure fluid for actuating said valve, and manually operable means including an element arranged coaxially with said distribution valve and extending therethrough and having valve means for establishing communication between the valve chest spaces at the opposite ends of the valve, said element also having means for directly engaging said valve to shift and hold the latter immovable.

4. In a fluid actuated rock drill of the hammer type, the combination of a cylinder and a hammer piston reciprocable therein, a valve chest and a fluid distributing valve therein for controlling both the supply and exhaust of pressure fluid for said cylinder, valve throwing passages between opposed spaces in the valve chest and the cylinder bore for supplying pressure fluid for actuating said valve, and a hole blowing device comprising a valve arranged coaxially with said distribution valve and having a by-pass therein for directly connecting said opposed valve chest spaces to equalize the throwing pressures acting on the opposite ends of said distribution valve, and means for positively shifting and holding said distribution valve in one position.

5. In a fluid actuated rock drill of the hammer type, the combination of a cylinder and a hammer piston reciprocable therein, a valve chest and a fluid distributing valve therein for controlling both the supply and exhaust of pressure fluid for said cylinder, valve throwing passages between opposed spaces in the valve chest and the cylinder bore for supplying pressure fluid for actuating said valve, and a hole blowing device comprising a valve arranged coaxially with said distribution valve and extending therethrough and having a by-pass therein for directly connecting said opposed valve chest spaces to equalize the throwing pressures acting on the opposite ends of said distribution valve, and means for positively shifting and holding said distribution valve in one position.

6. In a fluid actuated rock drill of the hammer type, the combination of a cylinder and a hammer piston reciprocable therein, a valve chest and a fluid distributing valve therein controlling both the supply and exhaust of pressure fluid for said cylinder, valve throwing passages between opposed spaces in the valve chest and the cylinder bore for supplying pressure fluid for actuating said valve, and a hole blowing device comprising a manually operable valve means arranged coaxially with said distribution valve and extending therethrough for establishing communication be-

tween said opposed valve chest spaces, and means for positively shifting and holding said distribution valve in one position.

7. In a fluid actuated rock drill of the hammer type, the combination of a cylinder and a hammer piston reciprocable therein, a valve chest and a fluid distribution valve therein controlling both the supply and exhaust of pressure fluid for said cylinder, valve throwing passages between opposed spaces in the valve chest and the cylinder bore for supplying pressure fluid for actuating said valve, and a hole blowing device including a manually operable plunger valve arranged coaxially with said distribution valve and extending therethrough and having a by-pass therein for directly connecting said opposed valve chest spaces for equalizing the pressures at the opposite ends of said valve, and means for mechanically shifting and holding said valve in one position.

25 8. In a fluid actuated rock drill of the hammer type, the combination of a cylinder and a hammer piston reciprocable therein, a valve chest, a fluid distribution valve therein controlling both the supply and exhaust of pressure fluid for said cylinder, buffer plugs for limiting movement of said valve in opposite directions, said plugs each having a central bore and ports connecting said bores with opposed spaces in the valve chest at the opposite ends of the valve, valve throwing passages between said opposed spaces and the cylinder bore for supplying pressure fluid for actuating said valve, and a hole blowing device including a manually operable plunger valve arranged coaxially with said distribution valve and slidably mounted in the bores in said buffer plugs, said plunger valve having a by-pass therein for connecting the ports in said buffer plugs to equalize the pressures at the opposite ends of said distribution valve, and means for mechanically shifting and holding said valve in one position.

45 9. In a fluid actuated rock drill of the hammer type, the combination of a cylinder and a hammer piston reciprocable therein, a valve chest and a fluid distributing valve therein controlling both the supply and exhaust of pressure fluid for said cylinder, valve throwing passages between opposed spaces in the valve chest and the cylinder bore for supplying pressure fluid for actuating said valve, and a hole blowing device including a manually operable plunger valve having means for establishing direct communication between said opposed pressure spaces for equalizing the pressures tending to throw said distribution valve, and means for mechanically shifting and holding said valve in one position.

10. In a fluid actuated rock drill of the hammer type, the combination of a cylinder and a hammer piston reciprocable therein, a valve chest and a fluid distribution valve

therein controlling both the supply and exhaust of pressure fluid for said cylinder, valve throwing passages between opposed spaces in the valve chest and the cylinder bore for supplying pressure fluid for actuating said valve, and a hole blowing device including a manually operable plunger valve arranged coaxially with said distribution valve for establishing communication between said opposed pressure spaces for equalizing the pressures tending to throw said distribution valve, and means for mechanically shifting and holding said valve in one position.

11. In a fluid actuated rock drill of the hammer type, the combination of a cylinder and a hammer piston reciprocable therein, a valve chest and a fluid distribution valve therein controlling both the supply and exhaust of pressure fluid for said cylinder, valve throwing passages between opposed spaces in the valve chest and the cylinder bore for supplying pressure fluid for actuating said valve, and a hole blowing device including a manually operable plunger valve arranged coaxially with said distribution valve and extending therethrough for establishing communication between said opposed pressure spaces for equalizing the pressures tending to throw said distribution valve, and means for mechanically shifting and holding said valve in one position.

12. In a fluid actuated rock drill of the hammer type, the combination of a cylinder and a hammer piston reciprocable therein, a valve chest and a fluid distribution valve 100 therein controlling both the supply and exhaust of pressure fluid for said cylinder, valve throwing passages between opposed spaces in the valve chest and the cylinder bore for supplying pressure fluid for actuating said valve, and a hole blowing device including a manually operable valve for establishing communication between said opposed valve chest spaces to equalize the pressures tending to throw said distribution valve, said 110 valve being adapted to directly engage said distribution valve for shifting and holding the latter immovable to effect a hole blowing operation.

13. In a fluid actuated rock drill of the hammer type, the combination of a cylinder and a hammer piston reciprocable therein, a valve chest and a fluid distributing valve therein controlling both the supply and exhaust of pressure fluid for said cylinder, valve throwing passages between opposed spaces in the valve chest and the cylinder bore for supplying pressure fluid for actuating said valve, and a hole blowing device including means for establishing communication between said opposed valve chest spaces to equalize the pressures tending to throw said valve and for directly engaging

said distribution valve to shift and hold the latter immovable to effect a hole blowing operation.

14. In a fluid actuated rock drill of the hammer type, the combination of a cylinder and a hammer piston reciprocable therein, a valve chest and a fluid distributing valve therein controlling both the supply and exhaust of pressure fluid for said cylinder, valve throwing passages between opposed spaces in the valve chest and the cylinder bore for supplying pressure fluid for actuating said valve, and a hole blowing device including means arranged coaxially with said distribution valve for establishing direct communication between said opposed valve chest spaces for equalizing the pressures tending to throw said valve, and means for mechanically shifting and holding said valve in one position to effect a hole blowing operation.

In testimony whereof I affix my signature.

CHARLES F. OSGOOD.
